UNITED STATES PATENT OFFICE.

MILTON R. STRUNK, OF BOYERTOWN, PENNSYLVANIA, ASSIGNOR TO BOYERTOWN BURIAL CASKET CO., OF BOYERTOWN, PENNSYLVANIA, A CORPORATION OF PENNSYLVANIA.

DESIGN FOR A CASKET.

Application filed March 4, 1922. Serial No. 1,022. Term of patent 14 years.

To all whom it may concern:

Be it known that I, MILTON R. STRUNK, a citizen of the United States of America, residing at Boyertown, in the county of Berks and State of Pennsylvania, have invented a new, original, and ornamental Design for Caskets, of which the following is a specification, reference being had to the accompanying sheet of drawings, forming a part thereof.

I claim:

The ornamental design for a casket, as shown.

MILTON R. STRUNK.
